STEAM IRON

Alan D. Smith, Mansfield, Ohio, assignor to Westinghouse Electric Corporation, East Pittsburgh, Pa., a corporation of Pennsylvania

Filed Mar. 20, 1962, Ser. No. 181,113

3 Claims. (Cl. 38—77)

This invention relates to an electrically heated flatiron, especially a steam iron also useful as a dry iron.

Electrically heated flatirons normally have a resistance heating element in the soleplate and have a thermostat in conjunction therewith to maintain the soleplate at the desired temperature. The thermostat is manually adjustable to permit selection of appropriate ironing temperature for fabrics of various compositions. While the thermostat necessarily is located at or near the soleplate, the adjusting means preferably is at a cooler location, where it can be manipulated readily by the user of the iron. A temperature scale calibrated according to fabric composition is a customary accompanying feature.

Steam irons have, in addition to such provisions for temperature control, certain apparatus features necessitated by the adaptation for steam ironing. These may include one or more manual controls for limiting the admission of water into a storage reservoir, and the emission of water therefrom, as into a "flash" or vaporization chamber, for example. Of course, these controls also must be readily available to, but not unnecessarily in the way of, the user of the iron. As proper operation and whole-hearted acceptance of the iron by the consumer depend upon simplicity and reliability of the respective control features, as well as of the rest of the mechanism, it is desirable to minimize the manipulations required thereby on the part of the user of the iron.

A primary object of the present invention is simplification of the manipulative control features of a steam iron.

An object is provision of a steam iron with unified control of temperature and of water content.

Another object is preset correlation between the rate of steam generation and the ironing temperature of a steam iron of the "flash" type.

A further object is compact construction of temperature-regulating means for an electric iron.

Other objects of this invention, together with means and methods of attaining the various objects, will be apparent from the following description, and the accompanying diagrams, of a preferred embodiment of the invention.

FIG. 1 is a view in side elevation, largely in section, of an electric iron in accordance with the present invention;

FIG. 2 is a perspective view, partly in section, of a portion of the article of FIG. 1, including mechanical linkages responsive to various settings of the control knob visible at the upper left;

FIG. 3 is an enlarged plan view of the upper anterior portion of the article of FIG. 1, including indicia for various settings of the superimposed control knob; and

FIG. 4 is a schematic representation of the positions of certain cam elements of FIGS. 1 and 2 at various settings of the control knob.

In general, the objects of the present invention are accomplished, in a steam iron having an electrical heating element for the soleplate thereof and a thermostat for controlling the soleplate temperature and having a water reservoir and means for controlling changes in the amount of water in the reservoir, by movable cam means having thereon, in fixed relation to one another, respective cam surfaces for temperature control and water control.

2

The invention contemplates particularly, in temperature-control means for such an iron, a disc-shaped cam member pivoted on a vertical axis, with reference to normal ironing orientation, a yoke generally surrounding the cam member and pivoted on a horizontal axis, a cam surface for temperature control on the upper face of the cam member, a cam follower on the yoke and in juxtaposition to the cam surface, spring means biasing the cam follower into contact with the cam surface, and a connecting rod substantially diametrically opposed to the location of the cam follower and depending from the yoke.

FIG. 1 shows steam iron 10, in side elevation, largely in medial section (from toe to heel). Part of handle 11, water reservoir 12 and soleplate 13, together with certain components located on or near the medial plane, appear in solid, while the rest of these parts and most of the other illustrated parts are sectioned vertically (with reference to the normal ironing orientation shown in this view). U-shaped bracket 14, which is secured to the soleplate by cap screws 15 (one visible), supports the reservoir and surrounding shell 16, which substantially entirely covers the soleplate. Handle 11 is secured to the top of the shell by screws 18 (one visible) threaded upward into base portion 19 of the handle through suitable apertures in the shell. The base portion joins the visible front and rear handle portions, which also are joined by grip portion 20 spaced above and generally paralleling the base. Bolt 21 surrounded by sleeve bushing 22 extends through eye 23 of the reservoir and secures the shell to the U-shaped lower and upper washers 25 and 26 respectively, both the bracket by means of a nut 24 at the upper end and lower and upper washers 25 and 26 respectively, both the bracket and the shell having suitable apertures therein. A cover plate 27 for the nut 24 on bolt 21 snaps into opening 28 in handle base 19.

The soleplate has an electrical heating element 31, preferably of the sheathed type, embedded in it. The electrical leads for the heating element originate at cord 35, which extends from an external source of electrical potential (not shown) through grommet 36 fitted in the rear portion of handle 11 and into hollow 41 therein. This rear hollow in the handle opens downwardly into opening 42 in shell 16. The shell slopes downward and outward at the rear to overhang the heel of the soleplate, and the overhang is closed by access plate 43 attached by screws 44 to offset bracket 45. The offset bracket is secured by screws 47 to a pair of bosses 46 spaced transversely from one another on the upper face of the soleplate, as appears more clearly in perspective in FIG. 2 (only one boss 46 being visible, however).

Thermostatic switch 51 comprises rigid arm 52 and shorter bimetal arm 53 underneath it. The arms are riveted to one end of respective flexible strips 54 and 55, which are affixed at their opposite ends to upper and lower terminal strips 56 and 57. Insulating block 58 on the portion of offset bracket 45 overlying and bridging bosses 47 of the soleplate spaces the upper terminal strip from the offset bracket, while the lower strip is spaced therefrom by insulating strip 59 affixed to the underside of the support bracket between the bosses. The upper terminal strip has electrical lead 62 secured to its upturned end by screw 63. This lead joins one of the pair of leads from cord 35 (at insert 65 retained in the handle) in hollow 41 of the handle after passing through opening 42 in the intervening shell. The other lead from the cord terminates at a like insert (hidden from view) at which it is connected to a hidden end of the heating element by a suitable interconnecting lead (not shown). Electrical lead 67, which is secured to the upturned end of the lower terminal strip by screw 66, connects to the other end of

the heating element, an exposed portion of sheath 32 thereof appearing about a fourth of the way to the toe or forward end of the iron. Rigid arm 52 of the thermostat carries electrical contact 68 opposite electrical contact 69 on bimetal arm 53.

The forward end of the rigid arm has riveted to it insulating strip 71, which has opening 72 in it. Split lower end 73 of connecting rod 74 is clinched about the marginal portion provided by the opening in the insulating strip so as to provide a pivotal interconnection therewith. The connecting rod, which is adapted to move upward and downward as indicated by the double-headed arrow nearby, extends upward through eye 75 in reservoir 12 into hollow 81 in the forward portion of handle 11, where it threads into the lower end of elongated hex nut 76, the other end of which is secured to the bight of U-member 77 by screw 78 through a suitable aperture therein. The ends of the U-member are pinned pivotally to the ends of yoke 80, which extends forwardly therefrom. The yoke is supported on a pair of horizontal pivot pins 82 (visible in FIG. 2) through upturned ears 83 on support plate 84. The support plate rests at its opposite side edges on front and rear steps 86 and 87 (one of each being indicated in FIG. 1) in the interior wall of the surrounding handle and is secured thereto by screws 88 (one visible).

Support plate 84 supports, in addition to yoke 80, generally disc-shaped member 91, which is secured pivotally on the upper surface of the support plate by downwardly extending headed rivet 92, which has a retaining washer 93 at its lower end. The disc-shaped member has upper cam surface 95 and lower cam surface 96 on its respective faces. Tang 97, which extends upwardly and rearwardly from the bight of yoke 80, has threaded through it (in a suitable aperture in its horizontal portion) headless screw 99, which is juxtaposed the upper cam surface as a cam follower therefor. Pair of torsion springs 102 surrounding yoke pivot pins 82, and bearing against the upper rear surface of the support plate and the upper edge of the bight of the yoke, bias the bight of the yoke downward to bring the headless screw into contact with the upper cam surface. It will be apparent from the previous description of linkage between the yoke 80 and rigid arm 52 of thermostatic switch 51 that temperature regulation is accomplished by means of the upper cam surface and its follower through the medium of such linkage and the yoke itself.

Disc-shaped member 91 has extending from the portion of it located at the left (i.e., front) in FIGS. 1 and 2 offset support strip 103 for control knob 104. This support strip extends radially from its junction with the disc-shaped member, then upwardly, and finally further outwardly parallel to the radial direction and through slit 105 (v. FIG. 1) between the top edge of wall 106, which surrounds front hollow 81 in the handle, and cover 107 for the hollow. The cover fits snugly against the inside edge of the wall at the top of the hollow, and the slit extends throughout an arc of slightly more than one-half of a circle, at the front and the opposite sides. The control knob has pointer 108 extending radially inward toward the vertical axis of the disc-shaped member and over the outer edge of indicia plate 109 affixed to the top surface of the cover. The indicia plate, with the control knob superimposed thereon, appears in plan in FIG. 3, which is discussed hereinafter.

Passageway 111 for water is provided in the front of wall 106 of the handle. This passageway does not communicate with hollow 81 but is adapted to communicate (downwardly) with reservoir 12 when the control knob is moved to the extreme counter-clockwise position, as hereinafter more fully explained. The reservoir terminates in collar 112 immediately beneath the inner downwardly oriented terminus of passageway 111 and is sealed to surrounding portion 113 of the handle by intervening gasket 114. Shown seated against this portion of the

handle and thereby closing the passageway off from the reservoir is sealing disc 115, which is somewhat smaller in diameter than the gasket. The sealing disc has an axial bore therein through which passes valve stem 121.

5 Clamp 122 on the valve stem about midway between the base and the collar of the reservoir supports washer 123, while compression spring 124 surrounds the valve stem between that washer and washer 125, which lies against the underside of the sealing disc. The lower end 10 of the valve stem is rounded to conform to valve seat 126 and terminates in pilot probe 127 shown in place in throat 128 of the valve. The valve seat and throat are formed in valve insert 129, which forms the outlet for water from the reservoir. The upper end of the valve stem fits snugly but slidably in a bore 131 in that portion 15 of the handle wall separating passageway 111 and hollow 81. Affixed to the portion of the valve stem in the passageway is clamp 132. Loosely surrounding the valve stem below this clamp is collar 133 of figure-8 clamp 134.

20 Figure-8 clamp 134 also encircles push rod 135 (which parallels valve stem 121) and is affixed thereto by set screw 136. The push rod terminates at its lower end near the upper surface of sealing disc 115 and extends upward from clamp 134 slidably and snugly into and through bore 137 paralleling bore 131 in the handle wall. Compression spring 138 is retained about the push rod between the upper surface of the adjacent wall (about bore 137) and clamp 139, which is affixed to the rod. The upper end of the push rod is juxtaposed to (lower) cam 25 surface 96 on the under face of disc-shaped member 91 and is biased into contact therewith as a cam follower by the compression spring 138. It will be apparent that the push rod and parallel valve stem, together with their associated parts, are instrumental in controlling the admission of water into and emission of water from reservoir 30 (as is described more fully hereinafter). To the extent that the structure thereof constitutes subject matter of a patent application of Samuel R. Bricker, Serial No. 179,357, filed March 13, 1962, it is excluded from the present invention, the subject matter of the present application.

35 Valve insert 129, flanged at its upper end just inside reservoir 12, extends downwardly (v. FIG. 1) to and through cover plate 141 for soleplate 16 and into vaporization chamber 142. Surrounding the intervening peripheral portion of the insert is packing 143, which is retained in place by packing gland 144 crimped to the upper face of the cover plate, which in turn is secured to the soleplate by screws. The underside of the cover plate is provided with channels 145, which conjoin channels 146 in the upper surface of the soleplate and interconnect the vaporization chamber with steam discharge ports 147 (only one being visible) through the base of the soleplate. Pressure-equalizing tube 148 extends from 40 one of channels 145 through the packing beside the valve seat and through grommet 149 located in a suitable aperture in the bottom of the reservoir and terminates inside collar 112 of the reservoir.

45 The operation of this iron is readily understood, especially by reference to FIG. 3, previously mentioned, which shows (in plan) indicia plate 109 on cover 107. Part of wall 106 of the handle is visible out from under the cover and the indicia plate, and control knob 104 is located at the left (front edge) with its pointer 108 extending back over the plate. A printed scale on the plate 50 is divided into four panels, each with indicia or legends, as follows (reading clockwise):

55 OFF WASH-WEAR
151, FILL; 152, LO SYN HI; 153, WOOL COT LIN
70 and
STEAM
154, LO HI

The pointer of the control knob rests on WOOL in FIG. 75 3, corresponding to its position in FIGS. 1 and 2. The

meaning of the respective legends is immediately apparent, and will be most readily understood in their relation to the associated mechanism by reference to the next view.

FIG. 4 is a schematic representation of the upper and lower cam surfaces and the positions of their respective cam followers (headless screw 99 and push rod 135) for control of both temperature and water throughout the range of possible settings of the control knob (not shown in this view). The cam surfaces are developed, i.e., laid out in the plane of the paper, representing corresponding positions of the cam followers (indicated adjacent thereto, aligned with one another). Of course, control knob 104 is movable manually throughout the entire width of all four panels 151, 152, 153, and 154, a total of approximately two hundred ten degrees. The representation of the respective cam followers, shown in solid in alignment with the word WOOL in the left portion of third panel 153, as compared with phantom (broken line) representations thereof elsewhere within the range presented by the four panels, corresponds to the setting of the control knob in the preceding views.

When control knob 104 is positioned at the furthest counterclockwise location (at the extreme left in FIG. 4) both cam followers are at their lowest positions. The extreme low position of the upper cam follower corresponds to such a high position of rigid arm 52 of the thermostatic switch that contacts 68 and 69 are not contiguous at any ordinary ambient temperature; this open circuit to the heating element leaves it unenergized or OFF so that the iron does not become heated. The extreme low position of the lower cam follower corresponds to a position in which push rod 135 depresses sealing disc 115 by contact therewith (as indicated by the arrow in FIGS. 1 and 2), permitting water to be introduced into reservoir 12 through passageway 111. The iron usually is tipped up on its heel to orient the passageway for easier introduction of water at this FILL position. It will be apparent that when the control knob is centered over panel 151, rather than at the extreme left thereof, the lower cam follower rises (biased by compression spring 138) along the lower cam surface to a higher level, at which the sealing disc is biased closed by compression spring 124. At both these positions of the lower cam follower, valve stem 121 is biased downward against valve seat 126 by compression spring 124, so no water can be emitted from the reservoir into vaporization chamber 142.

The lower cam follower remains at this neutral level at all positions of knob 104 throughout an intermediate range provided by the next two panels, 152 and 153, as the lower cam surface is horizontal through both of them, while the upper cam follower follows a rising cam surface, corresponding to increasing "dry" ironing temperatures. It is apparent that higher and higher positions of the upper cam follower correspond to lower and lower positions of rigid arm 52 of the thermostatic switch, closing the contacts so that bimetal arm 53 must bend downward farther and farther at its free or contact end (under the influence of increasing soleplate temperature) to open the energizing circuit to the heating element. The action of the thermostatic switch itself is wholly conventional.

As knob 104 reaches the fourth (or extreme clockwise) panel 154, however, the upper cam follower declines to a position almost, if not quite, as low as its position at the beginning of the dry ironing range at the left side of panel 152 (WASH-WEAR, etc.) and then rises again on a steeper incline to terminate at a level almost as high as the maximum reached at the right side of panel 153 (WOOL COT LIN). As indicated by the legend thereon, this last panel 154 covers the range of settings of the control knob for STEAM ironing. The lower cam follower rises gradually at the left side of this panel to a higher level, corresponding to withdrawal

of the lower end of valve stem 121 away from valve seat 126. The valve opens in this manner as the bias of compression spring 124 on the valve stem is overcome by the bias of stronger compression spring 138, which moves push rod 135 upward as permitted by the lower cam surface and thereby lifts the valve stem by contact of figure-8 clamp 134 with clamp 132 on the valve stem. When the valve is open, water present in the reservoir may pass (usually drop by drop) into vaporization chamber 142, where it is flashed to steam, which passes through conjoined channels 145 and 146 and out through discharge ports 147 in the base of the soleplate. Graduation of the opening of the valve over the lower portion of the STEAM temperature range prevents spitting of unvaporized water through the discharge ports.

All through the "dry" ironing range of water content of the reservoir is fixed, no water being allowed to leave by way of the drip valve, to be converted to steam, nor allowed to splash out of the reservoir by way of the inlet passageway. A convenient setting is provided, available only when the iron is turned off, for opening the inlet passageway to permit addition of water to the reservoir, and a suitable range of operating temperatures is provided at settings for STEAM ironing. The compact design and disposition of the linkages for the various controls in the hollow interior of the front portion of the handle is especially advantageous, not only facilitating location of the control knob at the most desirable operating location but also rendering the mechanism readily available from the exterior in the event that some maintenance should be required. Manufacturing economy is an additional advantage of this simplified unitary control arrangement.

The illustrated and described embodiment of this invention is exemplary, and modifications may be made therein without involving a departure from the invention. Parts may be combined or divided, changed in size, shape, or orientation, and even possibly omitted while maintaining the advantages and benefits of this invention, some of which have been mentioned above and others of which will be come apparent to and be enjoyed by those undertaking to practice the invention as claimed.

What is claimed is:

1. In temperature-control means for an electrically heated flatiron having a thermostatic switch with an adjusting arm and a bimetal arm adapted to bend away from the adjusting arm at ironing temperatures, the respective arms having electrical contacts opposing one another thereon and adapted to close when the temperature of the iron is less than required by the position of the adjusting arm, the thermostatic switch being located in the rear half of the iron, and the adjusting arm extending forwardly therefrom, the iron also having an attached handle extending fore and aft, the combination of a manually movable knob located near the foremost and topmost part of the handle, a cam member pivoted on a substantially vertical axis, with reference to normal ironing orientation, in the interior of the handle, the knob being adapted, upon movement thereof, to pivot the cam member, a yoke generally surrounding and spaced from the cam member and disposed generally horizontally, pivot means supporting the yoke for movement about a substantially horizontal axis intermediate its ends with its closed end forwardly and its open end rearwardly of said axis, a cam surface on the cam member, a cam follower on the yoke adjacent the closed end thereof and juxtaposed to the cam surface, and mechanical linkage interconnecting the open end of

the yoke and the forward end of the adjusting arm of the thermostatic switch.

2. A steam iron comprising a soleplate having a vaporization chamber and discharge ports therefrom through the base of the soleplate, an electrical heating element for the soleplate, a thermostat for controlling the temperature to which the soleplate is heated, a water reservoir, means for controlling the admission of water into the reservoir and the emission of water from the reservoir into the vaporization chamber, movable cam means having a first cam surface for the thermostat and a second cam surface for the water-control means, a first cam follower juxtaposed to the first cam surface, mechanical linkage operatively connecting the first cam follower to the thermostat, and a second cam follower juxtaposed to the second cam surface and operatively connected to the water-control means, said respective cam surfaces having two extreme position intervals and an intermediate range of positions, and wherein, at one extreme, the first follower is cammed to disconnect the electrical heating element, and the second cam follower is cammed to open the reservoir to the addition of water, in the intermediate range, the first follower is cammed through a range of temperatures suitable for dry ironing, and the second follower is cammed to seal off the water reservoir, and at the other extreme, the first follower is cammed within a narrower temperature range suitable for steam ironing, and the second cam follower is cammed to open the reservoir to the gradual loss of water for conversion into steam.

3. A steam iron comprising a soleplate having a

vaporization chamber and discharge ports therefrom through the base of the soleplate, and electrical heating element for the soleplate, a thermostat for controlling the temperature to which the soleplate is heated, a water reservoir, means for controlling the admission of water into the reservoir and the emission of water from the reservoir into the vaporization chamber, movable cam means having a first cam surface for the thermostat and a second cam surface for the water-control means, a first cam follower juxtaposed to the first cam surface, mechanical linkage operatively connecting the first cam follower to the thermostat, and a second cam follower juxtaposed to the second cam surface and operatively connected to the water-control means, the linkage connecting the first cam follower to the thermostat comprising a yoke supported pivotally at its opposite sides, with the movable cam means located spaced within the yoke, and with the first cam follower supported on the yoke intermediate the supporting pivots, and a connecting rod pivotally attached at one end to the opposite intermediate portion of the yoke, and at the opposite end to the thermostat.
